(57) CLAIM

The ornamental design for latch handle for refrigerator, as shown.

DESCRIPTION

FIG. 1 is a perspective view of latch handle for refrigerator looking from a right-side view thereof;

FIG. 2 is a perspective view of latch handle for refrigerator looking from a left side view thereof;

FIG. 3 is a perspective view of latch handle for refrigerator looking from a left-side under direction thereof

FIG. 4 is a front view thereof;

FIG. 5 is a rear view thereof;

FIG. 6 is a right-side view thereof;

FIG. 7 is a left-side view thereof;

FIG. 8 is a top view thereof;

FIG. 9 is a bottom view thereof;

FIG. 10 is a left-side view of latch handle for refrigerator looking from a left-side upper direction thereof;

FIG. 11 is a reference view (1) of latch handle for refrigerator showing the status of use of latch handle thereof; and, FIG. 12 is a reference view (2) of latch handle for refrigerator showing the status of use of latch handle thereof.

The broken lines showing of refrigerator and other fixtures in FIGS. 10-12 are for illustrative purpose only and form no part of the claimed design.
